UNITED STATES PATENT OFFICE.

JOHN NEWTON McNEES, OF HUGHESVILLE, MISSOURI.

GRAIN-BIN VENTILATOR, GRAIN-SAMPLER, AND WEEVIL-EXTERMINATOR.

No. 857,098.

Specification of Letters Patent.

Patented June 18, 1907.

Application filed April 4, 1907. Serial No. 366,426.

To all whom it may concern:

Be it known that I, JOHN NEWTON McNEES, a citizen of the United States, residing at Hughesville, in the county of Pettis and State of Missouri, have invented a new and useful Grain-Bin Ventilator, Grain-Sampler, and Weevil-Exterminator, of which the following is a specification.

This invention has relation to combined grain bin ventilators, grain samplers and weevil exterminators and it consists in the novel construction and arrangement of its parts as hereinafter shown and described.

The object of the invention is to provide a means for properly and effectually ventilating grain while it is stored in an elevator bin or other receptacle; also providing means whereby a sample of grain may be easily and readily taken from any particular part or level of the bin and furthermore providing means whereby the fumes of a germicide may be passed through the grain while in storage for the purpose of exterminating weevil and like vermin.

The device consists primarily of a foraminous pipe vertically disposed in the bin at a median line between the sides thereof, said pipe being provided at different points along its length with openings. A longitudinally movable rod is located in or adjacent the pipe and carries shields which normally close the openings in the pipe. Said shields are also provided with openings which, when the rod is moved longitudinally, are adapted to register with the openings in the pipe whereby exit means is afforded for the passage of the grain from the bin into the pipe. Thus, it is possible to take a sample of grain from any particular desired level of the bin. The said pipe is provided with foraminous branches which connect with the exterior and the shaft of the elevator and means is provided for leading air from the exterior of the bin into the bin.

In the accompanying drawing: — Figure 1 is a vertical sectional view of an elevator bin equipped with the ventilator, etc. Fig. 2 is a longitudinal sectional view of the ventilating pipe, and Fig. 3 is an enlarged sectional view of a portion of the same.

The elevator 1 is provided at its sides with the usual bins 2, 2 which are separated by the elevator shaft 3. The foraminous pipe 4 is vertically disposed in the bin 2 and is located at a median line between the vertical sides thereof. The said pipe is held in posi-

tion by the guys 5 which connect at their inner ends with the said pipe and at their outer ends with the sides of the bin. The pipe 4 is supported upon the inclined bottom 6 of the bin. The pipe 4 is provided at different points along its length with the openings 7. The foraminous branches 8 and 9 connect with the pipe 4 and are preferably in inclined position as illustrated, the branch 8 extending from the pipe 4 into the shaft 3 and the branch 9 extending from the pipe 4 through the outer side of the bin 2. The branches 8 and 9 join with the pipe 4 at different levels. The lower end of the pipe 4 enters the space 10 provided below the bottom of the bin 2. The rod 11 extends longitudinally of the pipe 4 and carries the shields 12. The said rod 11, together with the shields 12, may be moved longitudinally of the said pipe. The shields 12 are provided at suitable points with the openings 13. An opening 13 is located in the vicinity of each opening 7 of the pipe 4 but the distance between each opening 7 and the adjacent opening 13 is different from the distance between the remaining openings 7 and adjacent openings 13. By this arrangement of openings it is possible to bring any particular opening 13 in register with its adjacent openings 7 in the pipe 4 without having the remaining openings 13 and adjacent openings 7 in register and hence an exit may be provided at any predetermined level for permitting a sample of grain to flow from the bin 2 through the pipe 4. By thus sampling the grain at different points or levels of the bin it is possible to keep advised of the condition of the grain at such points or levels. The branch or branches 8 which lead into the shaft 3 are provided with similar means for sampling the grain. The branch or branches 9 are devoid of such means as they lead to the exterior of the bin. The last said branches act in the capacity of air ducts only. By reason of the foraminous nature of the pipe 4 and the branches 8 and 9 the air is permitted to pass through said pipe and branches and through the minute perforations thereof into the grain and prevent the same from sweating or molding.

The foraminous strips 14 are attached to the blocks 15 which are located between the uprights of the bin and which form a means for leading air from the outside into the bin. The opening to the strips 14 made by the space between the blocks 15 is covered by the

hood 16 attached to the outer side of the bin. The strips 14 and hoods 16 extend all of the way around the bin.

When it is desired to treat the grain to relieve the same of weevil or vermin the cap 17 is closed down over the top of the pipe 4 and the cap 18 is closed against the lower end of the said pipe. A bottle or vessel containing a germicide in liquid form is placed upon the cap 18 and within the lower end of the pipe 4. As the said germicide evaporates the fumes pass up the pipe 4 and as they cannot escape from the top thereof by reason of the fact that the top is closed they pass out laterally through the minute perforations in the pipe 4 and pass through the grain. When this operation has been carried on to such an extent as to kill the vermin the caps 17 and 18 are removed from the ends of the pipe 4 and fresh air is circulated through the grain to remove all traces of the germicide previously injected therein.

Having described my invention what I claim as new and desire to secure by Letters Patent is:—

1. In combination with an elevated grain bin, a foraminous pipe vertically disposed therein and passing through the bottom of

the bin, said pipe having at different points along its length openings, a movable rod extending parallel with the pipe and having shields provided with openings which are adapted to register with the openings in the pipe.

2. In combination with a grain bin having an adjacent shaft, means for introducing air into the shaft, a foraminous pipe vertically disposed in the bin and passing through the bottom thereof and a foraminous branch connecting said pipe with the shaft.

3. In combination with an elevated grain bin, a foraminous pipe vertically disposed therein and passing through the bottom of the bin, said pipe having at different points along its length openings, a movable rod extending parallel with the pipe and having shields adapted to close the openings in the pipe.

In testimony that I claim the foregoing as my own, I have hereto affixed my signature in the presence of two witnesses.

JOHN NEWTON McNEES.
